UNITED STATES PATENT OFFICE.

JOHN D. TAYLOR, OF SWISSVALE, PENNSYLVANIA, ASSIGNOR TO UNION SWITCH & SIGNAL COMPANY, OF SWISSVALE, PENNSYLVANIA, A CORPORATION OF PENNSYLVANIA.

TRACK-RELAY.

No. 870,139.

Specification of Letters Patent.

Patented Nov. 5, 1907.

Application filed April 18, 1907. Serial No. 368 997.

To all whom it may concern:

Be it known that I, JOHN D. TAYLOR, of Swissvale, Allegheny county, Pennsylvania, have invented a new and useful Track-Relay, of which the following is a full, 5 clear, and exact description, reference being had to the accompanying drawings, forming part of this specification, in which—

Figure 1 is a cross-section of the relay on the line I—I of Fig. 2; Fig. 2 is a sectional side elevation of the same; 10 and Fig. 3 is a diagrammatic view showing the track circuits and arrangement of the relay with an alternating current electric railroad.

My invention relates to the operating of block signals controlled by track circuits.

15 The principal object of the invention is to provide a relay which will operate only with a current of a given frequency, and will prevent incorrect operation of the signal, either by the unbalancing of the track circuit, by stray currents or otherwise.

20 The invention consists in an induction motor combined with a centrifuge or similar device which is selective by reason of different speeds at which it is driven by currents of different frequencies. This selective character is preferably imparted by a centrifuge, the speed of which must reach a certain predetermined rate before the signal can be operated.

25 The system is especially advantageous for alternating current electric road systems, though it may be employed for roads operated by direct current, or for steam roads, or roads having other systems of propulsion. In 30 the drawings, I show my invention as applied to an electric road having alternating current, both for the propulsion circuit and the signaling circuit.

Referring to Fig. 3, 2 represents the trolley wire or 35 third rail through which power is transmitted to the train, 3 being the source of current supply for propelling the train. 4 and 5 are sections of the rails forming what is known as a block, 6, 7, 8 and 9 being sections of rails in the adjacent blocks. The insulation between 40 the rails of the successive blocks is indicated at 11, 12, 13 and 14, this being preferably in the form of insulated rail joints. The rails of the track in the form shown, are employed for the return power current, and for this purpose, must be electrically connected around the insulated joints. I have shown this connection as afforded by inductive bonds 15, 16, 17 and 18, the current from the generator 3 being led into the middle points of the coils of the inductive bonds 15 and 16 by the wires 17' and 18'. This connection to the middle point of the 45 bond coil prevents any inductive action by the bond on the power current; while the bond offers an inductive resistance to the track circuit current which is supplied

to the track section by the secondary coil 19 of the track transformer. This track transformer is shown as energized by having its primary coil 20 connected to the mains 21 and 22 leading from an alternating current generator 23; and this generator has a current frequency greater than that of the generator 3.

The motor relay indicated at 24 is shown in detail in the preferred form, in Figs. 1 and 2. In these figures 25 is a laminated field piece of an induction motor of the "squirrel cage" type in which 26 indicates the laminated armature. The field piece is shown as having four inwardly-projecting poles each provided with an energizing coil. A copper band 27 known as a shading band is shown surrounding the corresponding half of each polar projection, this band being employed to cause a lag of the magnetic flux in the part of the pole surrounded by it, resulting in a torque on the armature which causes it to rotate. The centrifuge portion of the 70 relay comprises weights 28 attached to levers 29 pivoted to and rotating with the tubular shaft 30 of the induction motor. Through the tubular armature shaft extends a pin or rod 31, the lower end of which bears upon a bar 32 carried by links 32' depending from the centrifugal arms or levers. The rotation of the armature will cause the balls or weights to move outwardly and upwardly, and through the link connections will lift the bar 32 on which the rod 31 rests. The rod 31 carries at its upper end, the contact lever 33, having a contact 80 arranged to coact with the stationary contact piece 34. The contact will not be made until the shaft reaches a predetermined speed thereby moving the balls far enough to lift the contact lever 33 until the contact is made.

85 As shown in Fig. 3, the coils of the motor relay 24 are connected to the secondary 35 of a second transformer whose primary coil 36 is connected to the rails 4 and 5 near the entrance of the block section by wires or connections 37 and 38. 39 indicates the signal 90 having a source of current 40 with the circuit wires 41 and 42.

The induction motor of the relay depends for its speed solely on the frequency of alternation; and the speed is almost directly proportional to the frequency. 95 At a given frequency, the speed will have a certain fixed value, no matter whether the current through the motor be great or small. The force with which the weights are drawn out is proportioned to the square of the speed of rotation, so that it is an easy matter to differentiate between two current frequencies by the force tending to cause the weights to diverge. The parts of the apparatus therefore, can be so proportioned, that the force due to the lower frequency of alternation.

will not cause sufficient movement of the centrifuge arms to close the signal circuit; while if the motor is driven at a higher speed at or above the certain limit, the contacts will be closed. For example, I may use 5 a train propulsion current of the common frequency of twenty-five cycles per second; while the current supplied to the track signal circuit is sixty cycles per second. In this case, the motor will rotate 2.4 times as fast when energized by the track circuit current, as 10 when energized by the unbalancing of the train propulsion current. The weights will therefore be thrown out with nearly six times as much force when driven at the higher of the two speeds, than when driven at the lower.

15 In the operation of the system as shown, when there is no train in the block, the current from the secondary coil 19 will flow through the rails 4 and 5 and the primary coil 36 of the transformer. This will induce a current of the same frequency in the secondary coil 35 20 which will flow through the coils of the motor relay and cause a rapid rotation of its armature. This will raise the centrifuge arms and close the signal operating circuit at 34, thus clearing the signal. The inductive bonds 16 and 17 on account of their reactance, will permit 25 sufficient difference of potential to be developed between the rails 4 and 5, to cause the current to flow through the primary coil 36. When a train enters the block comprising the rails 6 and 7, the primary coil 36 of the transformer will be short circuited which will 30 prevent the flow of current through it, and accordingly prevent the induction of any current in the coil 35, thus depriving the motor relay of the power for rotating it. Its rotation will therefore cease, and the weights will return to their lower position, thus opening the 35 signal circuit, and causing the signal to resume the danger position by gravity. In case there is unbalancing of the track circuit due to difference in the resistance of the rails 4 and 5, current having the frequency of the train propulsion current, will pass through 40 the primary coil 36; and this may happen while a train is in the block comprising the rails 4 and 5. This current will of course induce a current of the same frequency as the propulsion current, in the secondary coil 35 of the transformer; but the rotation of the motor 45 relay caused thereby will be of too slow a rate to cause the closing of the signal circuit which will therefore not be cleared.

I have shown the transformer having the primary and secondary coils 36 and 35 placed between the relay 50 and the track. This device may be used to change the voltage passing to the relay; and theoretically it would reduce liability to interference with the proper operation of the relay by reason of unbalancing of the propulsion current. This transformer is, however, not necessary; and in most cases, I prefer not to employ it, but to connect the relay directly to the rails of the section. I have found in practice that with the ordinary alternating current employed for propulsion, no unbalancing which would ordinarily occur could interfere with 55 the proper operation of the relay. This transformer, therefore, may or may not be used, and in most cases would not be employed.

The advantages of my invention will be apparent to those skilled in the art. Improper operation of the signal is prevented by the selective action of the frequency relay. If the unbalancing of the propulsion current in the block should occur it cannot close the signal circuit, because its frequency is insufficient to give the centrifuge the speed necessary to close the circuit. The relay can only be operated when a current 65 is imparted thereto at a frequency high enough to give the speed for which it is designed to close the circuit. Wrongful operation of the signal is thus avoided, and the relay is operated with a much smaller current than is required with previous devices for this purpose. The 70 relay will operate equally well whether the propulsion current is direct current or alternating current. It may also be used for steam roads or roads having other systems of propulsion, where stray currents may be encountered. In such case it is of great advantage because it eliminates all danger of operating the signal from foreign direct current or foreign alternating current of a lower frequency than that employed for operating the relay. An induction motor is employed 75 as a part of the relay, and this preferably receives all 80 of its current from the track circuit through a single winding.

The selective action may be obtained electro-magnetically instead of mechanically, and many other changes may be made in the form of the selective speed 85 device portion of the relay, the circuits, etc., without departing from my invention, since I consider myself the first to use a selective relay whose operation depends upon its speed of rotation.

I claim:—

1. In a block signalling system, a track section connected to a source of alternating current of high frequency, and a relay comprising a motor whose speed of rotation is dependent on the frequency of the current, a centrifuge, driven by the motor, and a contact maker actuated by the centrifuge for closing a signal circuit when the speed of rotation corresponds to the frequency of the track circuit current.

2. In a block signalling system, a track section connected to a source of alternating current having a frequency greater than that of any foreign current in the track section, and a relay comprising an induction motor whose speed of rotation is approximately proportioned to the frequency of the current supplied to it, a centrifuge driven by the motor, and a contact maker actuated by the centrifuge for closing a signal circuit when the speed of rotation of the motor corresponds to the frequency of the track circuit current and is greater than that corresponding to the frequency of the foreign current.

3. A frequency relay containing an induction motor and a centrifuge together with a contact-making device actuated by the centrifuge for closing a signal circuit when the speed of rotation corresponds to the frequency of the track circuit current; substantially as described.

4. A frequency relay connected to the track circuit 120 and receiving its entire current therefrom, said relay containing an induction motor a centrifuge driven by the motor, and a contact maker actuated by the centrifuge for closing a signal circuit when the speed of rotation corresponds to the frequency of the track circuit current; substantially as described.

5. In a block system, a frequency relay containing an induction motor, and a centrifuge, said motor receiving alternating current of a certain frequency through the track circuit, which frequency is higher than any current 125

which may be communicated by unbalancing of the propulsion current or foreign currents; substantially as described.

6. In a block signalling system, an insulated track section connected to a source of alternating current of high frequency, and a frequency relay having a speed selective device arranged to operate the signal circuit; substantially as described.

7. In a block signalling system for electric railroads, an
10 insulated track section connected to a source of alternat-

ing current of higher frequency than the propulsion current, and a relay having a speed device arranged to operate a circuit when its speed reaches a predetermined rate; substantially as described.

In testimony whereof, I have hereunto set my hand.

JOHN D. TAYLOR.
